UNITED STATES PATENT OFFICE.

HENRY G. WITTBOLD, OF CHICAGO, ILLINOIS.

DESIGN FOR A CANOPY-FRAME.

SPECIFICATION forming part of Design No. 30,268, dated February 28, 1899.

Application filed December 27, 1897. Serial No. 663,772. Term of patent 8½ years.

To all whom it may concern:

Be it known that I, HENRY G. WITTBOLD, a citizen of the United States, residing at Chicago, in the county of Cook and State of Illinois, have invented and produced a new and original Design for Canopy-Frames; and I do hereby declare the following to be a full, clear, and exact description thereof, reference being had to the accompanying drawing, forming a part thereof.

The drawing is a view in perspective of a canopy-frame, showing my design.

The principal feature of my design is comprised in the corner-posts A A A A, the large

socket-feet a a a a, the horizontal connecting-bars B B on the four sides, the diagonal bars C C, and the stays b b.

Other features of the design are the center flagstaff D, the corner flagstaffs d d d d, and the stays g g g g.

What I claim is—

The design for a canopy-frame, substantially as herein shown and described.

HENRY G. WITTBOLD.
